(57) **CLAIM**

The ornamental design for a display screen with graphical user interface, as shown and described.

DESCRIPTION

FIG. 1 is a front view of a display screen with graphical user interface showing our new design;

FIG. 2 is a partial enlarged view taken along line 2-2 in FIG.

1 provided for clarify of illustration; and,

FIG. 3 is a partial enlarged view taken along line 3-3 in FIG. 1 provided for clarify of illustration.

The outermost evenly-spaced broken lines showing a display screen, as well as those evenly-spaced broken lines showing portions of the graphical user interface, are included for the purpose of illustrating portions of the article; the dot-dash broken lines define a boundary of the claimed design and form no part thereof; the dot-dot-dash broken lines indicate limits of enlarged views; all broken lines form no part of the claimed design. Additionally, it is understood that all portions of the graphical user interface outside the solid line regions form no part of the claimed design.

1 Claim, 3 Drawing Sheets
